UNITED STATES PATENT OFFICE

FRIGYES POTYIE, OF PHILADELPHIA, PENNSYLVANIA

PLASTERING MACHINE

Application filed March 7, 1929. Serial No. 345,102.

The present invention relates to an improved plastering machine particularly adapted for use in applying plaster to plain walls and partitions, the purpose being, in applying the plaster to operate a wet canvas against and to apply the plaster, a roller acting against the canvas or other flexible means, to not only spread the plaster and press it in shape, but due to the character of the face of the canvas, to leave a stucco finish or appearance.

Another purpose is to provide in a plastering machine a frame including a carriage on the frame, feeding guide rods in the frame and operated to actuate the carriage in a vertical direction, said carriage including means to support a roller in connection with a canvas kept thoroughly wet, whereby the roller may operate against the canvas as it unreels from a spring tensioned roller in the moisture or water trough, so that as the carriage operates perpendicularly on the frame, the plaster may be spread on the plain wall or partition, the canvas acting to leave a stucco finish or appearance.

Another purpose is to provide a mortar trough cooperating with the canvas apron and a smoothing roller, so that the mortar or plaster may be readily spread upon the surface to be plastered.

Another purpose is to keep the canvas apron thoroughly saturated with a moisture such as water or the like, so that as the canvas operates over the surface of the mortar or plaster, the latter will spread and adhere to the surface.

A great many of the plasters now used are usually worked or spread upon the wall or surface with a hand trowel and board or similar implements, which is more or less a tedious and lengthy job, and in the end there is left no finish of any kind. Whatever finish might be required must be subsequently applied.

Another purpose is to provide, in a plastering machine a roller operated canvas with an overlying mortar trough to protect the canvas on the roller from the plaster or mortar or the like as the plaster is spread on the surface, in combination with means on the

carriage on the frame to keep the canvas thoroughly moist as it unreels and spreads the mortar or plaster on the surface.

Another purpose is to provide in a plastering machine a frame, and a carriage guided perpendicularly thereon in combination with means for operating the carriage manually.

It is to be understood that the particulars herein given are in no way limitative, and that while still keeping within the scope of the invention, any desired modification of details and proportions may be made in the construction of the appliance according to circumstances.

The invention comprises further features and combination of parts to be hereinafter set forth, shown in the drawings and claimed.

In the drawings:—

Figure 1—is a view in side elevation of the improved plastering machine constructed in accordance of the invention and positioned adjacent a wall or other surface to be plastered.

Figure 2—is a plan view of the machine.

Figure 3—is an enlarged sectional view on line 3—3 of Figure 2 showing the upper part of the machine and more clearly showing the construction of the carriage.

Figure 4—is an enlarged detailed view of one end of a portion of the carriage, showing the roller operated canvas and illustrating the mortar trough and the spring tensioned roller for the canvas including the water trough, which may contain any suitable saturating means.

Figure 5—is an enlarged detailed sectional view of one of the bearings for one of the guide or operating rods.

Figure 6—is a detail view of the trough and its spring tensioned roller, showing the pintle 36 and slot 37.

Referring to the drawings 1 identifies a frame which may be any suitable shape, any height or otherwise suitably proportioned.

The frame is preferably elongated in a vertical direction, comprising an upper T-shaped section 2 and a lower section 3.

The lower section is of substantial rigid construction to support perpendicular rods 4 and 5. These rods are threaded throughout

their length, the threads being of any suitable design, there being requisite holding and lock nuts 4^a and 5^a at the top and bottom for cooperation with the upper and lower sections of the frame, to retain the sections in position and rigid relative to the rods. It is obvious that the rods which constitute portions of the frame may be any length though it is to be understood that the rods should correspond to the average height of a wall or partition to be plastered. However, every machine is to be equipped with various lengths of rods, so that a frame may be made to accommodate walls of different heights.

As previously stated the rods are threaded, and the frame, due to the bearings 6 and 7 of the top and bottom sections 2 and 3 is rigid, and operable on these rods, that is threaded thereon, are bushings 8 and 9, the bushings 9, as in Figure 1, being on the left side of the machine, while the bushing 8, as in Figure 1, is on the right hand side of the machine. These bushings are swiveled in bearings 10 of a carriage 11, there being ball bearings 12 to permit the bushings to operate freely, and as the bushings rotate the carriage moves vertically on the rods 4 and 5.

Mounted on the bushings 8 and 9 are the hubs 13 of the pinions or gears 14 and 15, the gear 14 being carried by the bushing 8, while the two gears 15 to the left, as in Figure 1, are carried by the bushings 9, there being set bolts or screws 16 to cause the gears to rotate with the bushings.

A vertical stub axle or stub shaft 18 is provided, and it has a disc base or flange 19, which is secured on the support or cross pieces 17 of the carriage 11, and journaled upon this stub axle or shaft is a center drive gear 20 provided with a hand wheel 21. This drive gear 20 meshes with the gears or pinions 14 and 15 and thereby impart movement thereto so as to feed the bushings perpendicularly on the rods 4 and 5.

The carriage 11 is provided with roller bearings 22, on which the under surface of the rim of the gear wheel 20 operates, so as to render the rotation of the gear 20 comparatively easy.

The carriage 11 has connected thereto an extension carriage 23, the connection being identified by the numeral 24. This extension carriage in plan view is substantially U-shaped or angular formation, and mounted upon the arms 25 of this extension carriage are the slotted sleeves 26, there being transverse pins 27 passing through the slots 27^a of the sleeves to limit the sleeves in their outward lateral movement. Interposed between the sleeves and collars 28 and in surrounding relation to the arms 25 are coil springs 29, which constitute yielding means for the sleeves.

Extending the length of the extension car-

riage and connecting the two slotted sleeves is a rocking rod 30, with which the supports 31 rock. These supports 31 are in the form of right angled levers, and certain of their arms assume substantially upstanding positions, while certain other of their arms assume substantially horizontal positions, and projecting from the upstanding arms are pins 32 on which a water trough 33 is mounted for slight swivel movement. In other words the pins 32 extend through the end walls of the trough.

Located within the trough is a spring tensioned roller 34, one similar to a shade roller, its spring, shown in Figure 6, being internally carried by the roller. This roller has a cylindrical pintle 35 at one end to engage in a depression in one of the pins 32, while the other end of the roller has a rectangular pintle 36 for engagement in a slot 37 of the other pin 32. Connected to the spring roller and wound thereon is a plastering sheet 38. This plastering sheet may be made of any pliable material such as heavy canvas or the like, or other material that will give the appearance of stucco work on the surface of the plaster. The water trough, in using the machine, is supplied with a quantity of water, thereby keeping the canvas or sheet 38 wet. This sheet or canvas passes over a smoothing or plastering roller 39 and has its other end connected in any suitable manner at 40 to the lower part of the frame of the machine.

The roller 39 is journaled in the substantially horizontal arms of the supports 31, which may be adjusted by rocking them, so as to dispose the roller 39 as may be desired. Whatever positions the supports 31 may assume, possibly engaged with the projections 31^a, as in dotted lines, the water trough 33 accommodates itself with respect to the spring tensioned roller, so as not to spill the water in the trough.

The sleeves 26 are provided with extension arms 41, which have teeth 42, and carried by the substantially horizontal arms of the supports 31 are dogs or pawls 43, which may be disposed to engage with the teeth 42 so as to retain the supports 31 in their adjusted positions, said pawls being pivoted at 43^a.

The flanges 44 of the bushings support the carriage 11, certain of the ball bearings co-operating between the flanges 44 and the carriage.

The upper and lower parts of the frame of the machine are provided with wall props 45 and 46, to engage with the wall, in order to space the frame of the machine the proper distance from the surface to be plastered, in order to permit the plastering canvas or sheet to operate properly in applying the plaster.

A plaster or mortar trough 47 is carried by the substantially horizontal arms of the supports 31, and it has an inclined bottom with curved portions to more or less conform to

and be arranged over the canvas or sheet 38 at a point where it passes over the roller 39, the end flanges 48 of the mortar or plaster trough prevent the plaster or mortar from escaping from the ends. The end flanges 48 of the mortar trough 47 at their lower portions have notches 48^a which engage a shaft 48^b, carried by and connecting the horizontal arms of supports 31, in order to support the trough.

10 In the operation of the machine the canvas 38 is positioned at the lower part of the frame of the machine, and as the carriage is operated by turning the hand wheel 21 to lower the carriage the spring tensioned roller 34 will cause the canvas or apron 38 to roll on the roller 34. When the machine is adjusted in the proper position adjacent the surface to be plastered, the roller 39 is disposed close to the surface to be plastered, but not enough 20 as to cause the canvas to contact with the surface. The plaster or mortar is then filled in on the mortar trough between the end flanges 48, then the operator turns the hand wheel 21 operating the drive gear 20 and in turn imparting motion to the gears 14 and 15 causing the carriage to ascend on the vertical rods 4 and 5. As the carriage moves upwardly, the canvas or apron unrolls from the spring tensioned roller 34 and due to the 30 apron or canvas being wet as it passes over the roller 39 the mortar or plaster is pressed against the surface which is to receive the plaster, and due to the canvas being of a heavy weave the face of the plaster will be given 35 the appearance of a stucco finish. In order to arrange the roller 39 in the proper position so as to cause the canvas to apply the mortar or plaster, the supports 31 may be tilted and held in their adjusted positions by 40 means of the dogs or pawls 43.

The invention having been set forth, what is claimed is:

1. In a plastering machine, the combination with a frame having screw guide rods and provided with wall props, the latter adapted to bear against the wall or other surface which receives the plaster, of a carriage operable on the screw rods and having manually operated gear connections with the 45 rods whereby the carriage may be fed manually in a vertical direction on the rods, said carriage having an extension yieldably mounted thereon, and a plastering apron connected to the lower part of the frame and 50 having pay out connections with the extension of the carriage for applying the plaster to the wall, means operably associated with and on the extension carriage for saturating the apron, and means for regulating the position of the apron with relation to the wall to 55 be plastered, and a mortar trough associated with the plastering roller and the apron to retain the mortar between the apron and the wall to be plastered.

60 2. In a plastering machine, the combina-

tion with a frame having screw guide rods and provided with wall props, the latter adapted to bear against the wall or other surface to be plastered, of a carriage operable on the screw rods and having manually operated gear connections with the rods, whereby the carriage may be fed manually in a vertical direction on the rods, an extension frame yieldably mounted on the carriage, a plastering roller mounted in the extension frame, a moistening trough on the extension frame having a tensioned roller therein, a plastering apron connected to the lower part of the first frame and passing over the plaster roller and wound on the tensioned roller, a mortar trough operatively supported on the extension frame and substantially conforming to the apron where it cooperates with the two rollers, whereby as the carriage moves upwardly, the apron and the roller applied 70 mortar to the surface to be plastered.

3. In a plastering machine, an upstanding frame provided with wall props for spacing the frame from the surface of the wall to be plastered, said frame including guides, a carriage mounted on the guides and having elements carried thereby and threaded to the guides, means on the carriage operatively associated with the elements for moving the carriage vertically on the guides, an extension frame on the carriage, a plastering roller on the extension frame, an apron connected to the lower part of the first frame and engaged over the plastering roller and provided with payout connections with the upper part 90 of the extension frame, a mortar trough operatively supported on pintles of the plastering roller and substantially conforming to the apron at a point above the plastering roller, whereby as the carriage moves vertically 95 on the main frame mortar is applied to the surface to be plastered.

4. In a plastering machine, an upstanding frame provided with wall props for spacing the frame from the surface of the wall to be plastered, said frame including guides, a carriage mounted on the guides and having elements carried thereby and threaded to the guides, means on the carriage operatively associated with the elements for moving the carriage vertically on the guides, an extension frame on the carriage, a plastering roller on the extension frame, an apron connected to the lower part of the first frame and engaged over the plastering roller and provided with payout connections with the upper part 110 of the extension frame, a mortar trough operatively supported on pintles of the plastering roller and substantially conforming to the apron at a point above the plastering roller, whereby as the carriage moves vertically 115 on the main frame mortar is applied to the surface to be plastered, said extension frame being yieldable, allowing the mortar to be 120 evenly distributed.

5. In a plastering machine, a carriage having an extension frame provided with tiltable elements, means for holding the elements in different tilted positions, a plastering roller mounted in the lower parts of the elements, a moistening trough carried by the upper parts of said elements and having therein a tensioned roller, an apron passing over the plastering roller and into said trough and wound on the tensioned roller, an upstanding frame on which the carriage is guided, means for operating the carriage on the upstanding frame, one end of the apron being attached to the lower part of the supporting frame, and a mortar trough operatively supported on and associated with said elements and substantially conforming to the apron where it cooperates with both rollers, whereby as the carriage moves vertically, mortar may be applied to the surface to be plastered.
6. In a plastering machine, a carriage having an extension frame provided with tiltable elements, means for holding the elements in different tilted positions, a plastering roller mounted in the lower parts of the elements, a moistening trough carried by the upper parts of said elements and having therein a tensioned roller, an apron passing over the plastering roller and into said trough and wound on the tensioned roller, an upstanding frame on which the carriage is guided, means for operating the carriage on the upstanding frame, one end of the apron being attached to the lower part of the supporting frame, and a mortar trough operatively supported on and associated with said elements and substantially conforming to the apron where it cooperates with both rollers, whereby as the carriage moves vertically, mortar may be applied to the surface to be plastered, said extension frame being slidable on and yieldably connected to the carriage, whereby the mortar may be evenly distributed on the surface.
45. In testimony whereof he affixes his signature.

FRIGYES POTYIE.
